DESIGN FOR A DISPLAY FIGURE OF SPOOLS OF SEWING SILK AND THE LIKE

Albert B. Collingbourne, Elgin, Ill.

Application September 16, 1936, Serial No. 64,884

Term of patent $3\frac{1}{2}$ years

To all whom it may concern:

Be it known that I, Albert B. Collingbourne, a citizen of the United States, residing at Elgin, in the county of Kane and State of Illinois, have invented a new, original, and ornamental Design for a Display Figure of Spools of Sewing Silk and the Like, of which the following is a specification, reference being had to the accompanying drawing, forming part thereof.

In the drawing:

Fig. 1 is a front elevation of a display figure of spools of sewing silk and the like showing my new design.

Fig. 2 is a side elevation of the same.

I claim:

The ornamental design for a display figure of spools of sewing silk and the like as shown.

ALBERT B. COLLINGBOURNE.
